UNITED STATES PATENT OFFICE.

WILHELM SCHLOERMILCH, OF BERLIN, GERMANY.

WAVE-DETECTOR.

1,294,177.

Specification of Letters Patent. Patented Feb. 11, 1919.

Application filed March 13, 1912. Serial No. 683,530.

To all whom it may concern:

Be it known that I, WILHELM SCHLOERMILCH, a citizen of the Empire of Germany, and residing at Berlin, Germany, have invented certain new and useful Improvements in Wave-Detectors, of which the following is a specification.

The subject-matter of my invention is an apparatus, operating without an auxiliary 10 source of current, for rendering electric oscillations perceptible, in which the part sensitive to waves consists of two good electrically conducting electrodes which contact one with another and move slidingly one 15 on the other.

Such an arrangement which, when stationary, constitutes merely a short-circuit, acts when the contact pieces slide one on the other, as a wave-indicator which by far 20 excels all detectors known heretofore in sensitiveness when both the contact material and its surface and also the speed at which the contact pieces move relatively to one another are correctly chosen. In addition, 25 there is the great advantage that such a receiver cannot be injured either by atmospheric influences or by electric overloading or mechanical shocks.

Several illustrative embodiments of my 30 invention are represented by way of example in the accompanying drawing, wherein:

Figures 1 and 2 are diagrams and

Fig. 3 is an elevation diagrammatically 35 showing three different embodiments of the inventive idea on which the invention is based;

Figs. 4 and 5 are two diagrams of connections for wave-detectors according to my 40 invention, and

Figs. 6, 7 and 8 are front elevation, side elevation, and top plan view, respectively, showing a constructional form of my wave-detector according to Fig. 3.

Referring first to Fig. 1, the electrodes *a* and *b*, preferably silver or gold wire, permanently contact with one another, and one of them is reciprocated upon the other, the simplest way in which this may be brought 50 about being an electromagnetic interrupter as shown in Fig. 1.

In this figure, 15 indicates the electromagnetic interrupter operated by battery 16. The electrode wire *b* is attached to the 55 oscillating member 18 of the interrupter

through an insulated portion 17. By this arrangement the wire *b* is moved in rapid oscillations upon wire *a*.

In the embodiment shown in Fig. 2 the sliding contact is formed, on the one hand, 60 by two springs *a*¹ and *a*² and, on the other hand, by an endless wire *b*¹ running over the two rollers *c* and *d* which can be driven by a clockwork or by an electric motor (not shown). 65

In the embodiment shown in Fig. 3, the stationary contact piece is a preferably adjustable spring *a*³ and the movable contact piece a rotatable disk *b*² which can be driven in any suitable manner by a driving device. 70

The efficiency of my improved wave-detector may be substantially due to the resistance of the contact varying in very rapid succession in consequence of the microscopically small unevennesses of the contacting surfaces. The improved receiving device therefore has a certain similarity with the ticker. Whereas telegraphic signals received by the ticker, however, are perceptible in the telephone as noises very similar to 75 those produced by atmospheric disturbances, the acoustic form of the signals received by my improved device is so uniform that these cannot be confused with atmospheric disturbances. 85

For receiving signals, besides the ticker connections all those receiving connections which have proved satisfactory for contact-detectors are adapted for use with my improved device. The receiving connections 80 shown in the drawing by way of example have proved very satisfactory in practice for the new arrangement.

Referring to Fig. 4, the wave-detector *a*, *b* is located in a tuned oscillatory circuit *i*. 95 A telephone *c* having choking coils *g* and *h* connected in series therewith is connected in parallel with the detector.

In the arrangement according to Fig. 5 the sliding detector *a*, *b* is located in the 100 aperiodic circuit *k* which is coupled with the tuned oscillatory circuit *i*. In consequence of the long periods of discharge telephones having very great self-induction and therefore requiring a longer duration of closure 105 can be used. When such telephones are employed the choking coils *g* and *h* shown in Figs. 4 and 5 may be omitted.

In addition to the advantage of being able to use telephones of any desired self-induc- 110

tion, the most important advantage of my improved detector is the simplicity of its manufacture and of its operation.

Referring now to Figs. 6-8, this wave-
5 detector comprises a disk 1 provided with vanes and adapted to be rapidly rotated by a clockwork contained in the casing 12. The clockwork can be stopped or started as de-
sired by a handle 2. The point of a fine up-
10 wardly-bent platinum wire 3 bears against the underside of the disk 1. For adjusting the disk and platinum wire I provide different devices which adjust the point in two directions, namely, one adjusting device for
15 the vertical adjustment and thus the adjustment of the degree of pressure, and another adjusting device for radially adjusting the sliding point relatively to the axis of the disk. For the vertical adjustment are pro-
20 vided in reality two devices; the platinum wire is attached to a bushing 4 which can be rotated about a horizontal axle by a handle 5. This bushing is attached to a two armed lever 6 which can be rocked about a second
25 horizontal axle 8, by means of an adjusting screw 7. The first of these two latter de-
vices brings about the rough and the second the fine adjustment.

The entire pressure adjusting device just
30 described now is rotatable, about a vertical axle 9 so that the platinum wire can be ad-
justed radially relatively to the axis of the disk 1 and thereby the relative speed be-
35 tween the wire and disk may be varied at will. A bushing carrying a spare contact
wire may be pushed on a pin 10 so that, in the event of injury to the operating wire, a spare wire is immediately available.

From all the modifications shown and
40 described, it appears that the principal novel
feature of my invention is the employment
of two metal electrodes in a circuit without
an auxiliary E. M. F. which was necessary
heretofore in such cases. The circuit or cir-
45 cuits in which these electrodes are located
do not contain any source of E. M. F. under
normal conditions and carry only the cur-
rents produced by the received oscillations.
I shall therefore define in the annexed claims
50 the circuit containing said electrodes, a "nor-
mally dead" circuit in contradistinction to
similar devices known in the art, in which
the arrangement of the electrodes requires a
normally "live" circuit, that is to say a cir-
55 cuit in which a permanently active source of
E. M. F. is provided as one of its necessary
elements.

I claim:

1. In a wave detector, a circuit for elec-
60 tric oscillations, a resistance in said circuit,

a normally dead circuit shunting the said
resistance, an indicating device in the latter
circuit, and means independent of the elec-
tric oscillations for producing rapid vari-
ations in said resistance, whereby corre-
sponding variations are produced in the cur-
rents passing through the shunt circuit and
the indicator. *LL*

2. A wave detector comprising in combi-
nation a suitable stationary metallic elec-
trode, a movable metallic electrode contact-
ing with the stationary electrode, and means
for sliding the movable on the stationary
electrode at a suitable speed, a normally
dead electric circuit containing said elec-
trodes and a receiver, the sliding of said
electrodes upon each other causing a suc-
cession of rapid variations of resistance be-
tween the electrodes, and means for con-
ducting electrical oscillations through said
electrodes whereby said oscillations are per-
ceived in said receiver as sounds of substan-
tially constant amplitude. *LL*

3. A wave detector comprising in combi-
nation a stationary metallic electrode, a mov-
able metallic electrode contacting with the
stationary electrode, and means for sliding
the movable on the stationary electrode at a
constant speed, a normally dead electric
circuit containing said electrodes and a re-
ceiver, the sliding of said electrodes upon
each other causing a succession of rapid
variations of resistance between the elec-
trodes, and means for conducting electrical
oscillations through said electrodes whereby
said oscillations are perceived in said re-
ceiver as sounds of substantially constant
amplitude. *LL*

4. A wave detector comprising in combi-
nation two metallic electrodes, one being a
wire, the other a rotatable metallic disk, ad-
justable means for pressing said wire against
said disk and for radially adjusting said
wire relatively to said disk and means for
rotating said disk at a constant speed, a nor-
mally dead electric circuit containing said
electrodes and a receiver, the sliding of said
electrodes upon each other causing a suc-
cession of rapid variations of resistance be-
tween the electrodes, and means for con-
ducting electrical oscillations through said
electrodes whereby said oscillations are per-
ceived in said receiver as sounds of substan-
tially constant amplitude. *LL*

In testimony whereof, I affix my signa-
ture in the presence of two witnesses.

WILHELM SCHLOEMILCH.
